CLAIM

The ornamental design for a photovoltaic panel system as shown and described.

DESCRIPTION

FIG. 1 is a perspective view of a first embodiment of a photovoltaic panel system showing our new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is a perspective view of a second embodiment of a photovoltaic panel system with two panels in a position of use; and,

FIG. 9 is a perspective view of a third embodiment of a photovoltaic panel system with two panels in an alternate position of use.

The broken lines shown represent environmental subject matter and form no part of the claimed design.
